UNITED STATES PATENT OFFICE.

OTTO MELLIGER, OF BERN, SWITZERLAND.

APPARATUS FOR THE PRINTING OF COLORED DESIGNS ON WALLS OR OTHER LARGE SURFACES.

Application filed September 21, 1927, Serial No. 221,111, and in Switzerland September 21, 1926.

My invention relates to a hand-operated apparatus for the printing, chiefly to be used for the printing of patterns, in several colors, on interior walls, to replace wallpaper.

5 The apparatus fulfills its purpose by possessing several pattern-rolls, placed parallel to each other, every one of them being provided with color separately. The pattern-rolls are mounted on a loose frame which 10 may be manipulated by hand in such a way that when being passed over the surface to be printed, the rolls roll up, one after another. Besides, the rolls are so connected with each 15 other, that any one turning, makes the others turn, too, so that any turning position of one 20 roll corresponds to determined turning positions of the others. For this reason, the prints of the various rolls, the latter being rolled up on the surface to be printed, lie in determined positions to each other.

The enclosed drawings show my printing apparatus namely:

Fig. 1 side-view,
Fig. 2 view from below,
25 Fig. 3 front-view,

Fig. 4 is a slight modification of the invention.

The printing rolls 3 and three color rolls 4 are mounted, parallel to each other, to rotate, on a frame consisting of two forks 1 and 2, connected with each other and adjustable.

30 Rolls 4 are firmly fixed to their beams 5 and rolls 3, on the lower fork 1, and rolls 4, on the upper fork 2, are placed in a way that a color roll each presses slightly against a printing roll.

One of the arms of fork 2 is connected with the part bearing the handle by a joint 6, and 35 the loose ends of both forks form slits 7, in which a connecting rod 8 is placed, to keep the arms in the right distance, and whose middle part forms a handle.

To put in rolls 4, the connecting rod 8 is 40 pulled out and the arms spread outwards around joint 6.

One of the arms of fork 1 is connected with the part bearing the handle by a joint 6, and 45 clamp 9, so that it may be shifted outwards, to put in rolls 3. It is also feasible, because 50 of the possibility to shift one of the arms of fork 1, to use printing rolls 3 of different lengths, should the pattern to be printed require same.

Arms 10 are mounted on fork 2, and their 55 ends bear slits, through which clamping screws pass, holding fork 1. After loosening the clamping screws, fork 1 may be adapted to fork 2 through shifting arms 10 on the clamping screws.

60 On each end of the middle printing rolls 3 is firmly mounted a sprocket 11, of which each is connected, by a driving chain 12, with a wheel, which is fastened on the beam 5 of one of the outer printing rolls 3, in a way that 65 it may be released by means of a regulating screw 14. This regulating screw being loosened, the printing roll 3 may be turned without the other rolls turning.

65 Thus it is possible to adapt the outer rolls 70 to the inner roll exactly in such a way that, when the three rolls are being rolled up on a surface, the apparatus being pulled over the surface in a straight line, while the three printing rolls are touching the surface and 75 each being provided with color by its roll 4, the prints of the rolls 3 harmonize exactly as desired.

To work with the apparatus, one hand holds 80 handle 20 and the other the handle formed by the connecting rod 8, whereupon the printing rolls are rolled up on the surface to be printed and slightly pressed against it.

In the modification shown in Figure 4, the 85 printing rolls 3 carry on one end of their respective shafts 5 gears 11', interconnected through the intermediate pinions 12' mounted on the fork 1. Each gear 11' is fixed on its shaft 5 by means of a set screw 14' which may be loosened to render the respective printing 90 roll inoperative.

95 Printing apparatuses are known which have several printing rolls on the same beam, which are supplied with color by a color roll. Such apparatuses I do not claim as my invention since they only serve to print plain patterns, dots, rings and the like, and the parts of the pattern of various colors must be side by side.

100 I also know a printing apparatus that has two printing rolls which are separately supplied with color. These printing rolls are mounted on rods, made to slide in sleeves which are fastened pivotally on a fixed stand. On this apparatus, therefore, the printing 105 rolls are not mounted on, or carried by a freely movable frame, and I do not claim it as my invention.

Having thus described my invention, what I claim as new and what I desire to secure by Letters Patent is:

1. A hand operated apparatus for the printing of designs in several colors, especially upon walls to imitate wall paper, comprising an adjustable frame, a set of at least three printing rolls mounted in said frame, each of said rolls being supplied with a different color, and means normally interconnecting said rolls for rotating the latter in the same direction and at the same speed, said means capable of being disconnected from any one of the rolls, whereby the disconnected roll will become inoperative with respect to the remaining rolls.
2. A hand operated apparatus for the printing of designs in several colors, especially upon walls to imitate wall paper, comprising a frame, a set of at least three printing rolls mounted parallel to each other upon the frame, a color applying roll for each printing roll, each of said color applying rolls being supplied with a different color, a gear for each printing roll, a pinion carried by the frame and interconnecting the gears of the printing rolls to rotate the latter in the same
- 25

direction and at the same speed and means associated with each gear for loosening the same upon its respective printing roll whereby the same will become inoperative with respect to the remaining printing rolls.

3. A hand operated apparatus for the printing of designs in several colors, especially upon walls to imitate wall paper, comprising an adjustable frame formed of two superposed detachable parts, a set of at least three printing rolls mounted parallel to each other in the lower part of the frame, a color applying roll for each printing roll carried in the upper part of the frame, each of said color applying rolls being supplied with a different color, a gear for each printing roll, a pinion carried by the frame and interconnecting the gears of the printing rolls to rotate the latter in the same direction and at the same speed and means associated with each gear for loosening the same upon its respective printing roll whereby the same will become inoperative with respect to the remaining printing rolls.

In testimony whereof I affix my signature.

O. MELLIGER.
